CARLINE FOR CAR-ROOFS.

1,053,557.

Specification of Letters Patent. Patented Feb. 18, 1913.

Application filed July 15, 1912. Serial No. 709,495.

To all whom it may concern:

Be it known that we, WILLIAM S. BIDLE and JOSEPH A. COSTELLO, citizens of the United States of America, residing at 5 Cleveland, in the county of Cuyahoga and State of Ohio, have invented certain new and useful Improvements in Carlines for Car-Roofs; and we do hereby declare the following to be a full, clear, and exact description of the invention, such as will enable others skilled in the art to which it pertains to make and use the same.

This invention relates to improvements in metal carlines for car-roofs, and pertains 15 more especially to a carline comprising a trough adapted to bridge the space between and extend transversely of and through the upper portions and beyond the outer sides of the side plates of a car-roof-frame.

20 One object of this invention is to provide a carline which possesses great strength and durability in its end-portions.

Another object is to provide the end flange with which the carline is provided at 25 each end with a baffle-member extending up and down the outer side of said flange and adapted to prevent the passage of water from the outer side of a roofing-sheet (not shown) applied so as to overlap the outer side of said flange at one side of said baffle-member to the inner side of a roofing-sheet (not shown) applied so as to overlap the outer side of said flange at the opposite side of said baffle-member.

30 With these objects in view, and to the end of attaining any other advantage herein-after appearing, this invention consists in certain features of construction, and combinations and arrangement of parts, herein-40 after described, pointed out in the claims and illustrated in the accompanying drawings.

In said drawings, Figure 1 is a top plan of a carline embodying our invention and 45 shows the carline applied to the side plates of a car-roof-frame. Fig. 2 is a top plan of an end-portion of our improved carline applied to a side plate of a car-roof-frame and shows car-siding and fascia at the outer 50 side of said side plate. Fig. 3 is a vertical section on line 3—3, Fig. 2, looking in the direction indicated by the arrow. Fig. 4 is a vertical section on line 4—4, Fig. 3, looking inwardly. Fig. 5 is a vertical section 55 on line 5—5, Fig. 3, looking outwardly.

Figs. 2, 3, 4, and 5 are drawn on a larger scale than Fig. 1.

Referring to Fig. 1 of the drawings, A and A indicate the two laterally spaced horizontally arranged side plates of a car-roof-frame, and a metal carline embodying our invention and preferably composed of a steel-blank pressed into the shape required is shown applied to said side plates and comprises a trough B which is shown bridging the space between and extends transversely of and through the upper portions and beyond the outer sides of said side plates which of course are recessed or cut away in any approved manner to receive 70 said trough. The trough B is provided with two downwardly projecting end flanges b and b which are arranged at opposite ends respectively and transversely of the carline and adapted to overlap the outer sides of the 75 side plates A, and consequently the outer side of each side plate of a car-roof-frame provided with our improved carline is overlapped (see Figs. 2, 3, and 4) by the adjacent end flange of said carline, which flange 80 abuts against and forms a lateral abutment for said side of said side plate and projects downwardly from the bottom of the trough B and extends upwardly at the sides of the trough to the top of the trough. 85

The lower portion of the outer side of each side plate is overlapped by car-siding C which is covered at its upper edge by the fascia D which has the top thereof sloping downwardly and outwardly from the outer 90 side of said side plate.

Each end flange b has a laterally and outwardly projecting lower portion 8 which over-laps the top of the adjacent fascia D.

The trough B is provided at the top with 95 two laterally and outwardly projecting side flanges 10 and 10 which are arranged at opposite sides respectively of the trough and extend between and to the end flanges b, and Fig. 1 shows each side flange 10 provided with seats 12 for purlins or longitudinal members (not shown) of a car-roof-frame.

Each end flange b is provided at its outer side and centrally between its side edges 105 with a laterally and outwardly offset portion 13 which extends vertically upwardly from the laterally and outwardly projecting lower portion 8 of said flange to and above the adjacent portion of the bottom of the 110

trough B, and said bottom is offset upwardly, as at 14, centrally between the sides of the trough, and the offset portion 14 of said bottom extends longitudinally of the trough between the adjacent end flange and a point spaced inwardly from the adjacent side plate. Said offset portion 14 of said bottom connects with the upper end of the offset portion 13 of the adjacent end flange b, and gradually increases in height toward said flange b and extends above said flange and above the adjacent ends of the side flanges 10 of the trough. Said offset portion 14 of said bottom gradually decreases in width toward its inner end and preferably terminates in a point, as at 15, Fig. 2, at its inner extremity. Said offset portion 14 of said bottom and the connecting offset portion 13 of the adjacent end flange b form a hump which extends up and down said flange at the outer side of the flange, which hump is therefore arranged centrally between and spaced from the sides of the trough and projects above the side flanges 10 and above the adjacent end flange b. The offset portions 13 and 14 of each end-portion of the carline materially strengthen said end-portions, and the offset portion 13 of each end flange b and the adjacent end of the adjacent offset portion 14 of the bottom of the trough constitute an efficient baffle which prevents the passage of water from the outer side of a roofing-sheet (not shown) applied so as to overlap said flange at one side of said offset portion of said flange to the inner side of a roofing-sheet (not shown) applied so as to overlap the outer side of said flange at the opposite side of said offset portion of said flange, and it will be observed also that the hump formed by adjacent offset portions 13 and 14 has formed thereon, above said flange, a rounded seat 16 for a roofing-cap (not shown) to be employed in connection with said roofing-sheets. The sides of each end-portion of the trough where said end-portion extends through a side plate A diverge toward the adjacent end flange b to accommodate the provision of the adjacent offset portion 14 of the bottom of the trough and yet have enough water-conducting capacity in said end-portion, and not unimportant is the gradual decrease in width of each offset portion 14 of the bottom of the trough toward its inner extremity and the gradual decrease in height of said offset portion toward said extremity so as to prevent as little obstruction as possible to the passage of water to the adjacent end of the trough.

60 Each side flange 10 has its portions which overlap the top of the side plates offset downwardly, as at 17, at the sides of the trough, and each offset portion 17 forms a pocket having a horizontally arranged bottom 18 which forms a seat for the head e of

a vertically arranged bolt whose shank E extends through said offset portion and through and below the adjacent side plate, and a nut G is screwed onto the said shank at the bottom of said side plate. Our improved carline is therefore shown secured to the side plates by suitably applied bolts and nuts. We would remark however that each end-portion of the carline is also preferably secured to the adjacent side plate by a horizontally arranged bolt (not shown) and to this end the offset portion 13 of each end flange b is provided below the bottom of the trough with a lateral bolt-hole 20 which (see Fig. 3) is arranged in line endwise and consequently in registry with a bolt-hole 21 which is formed in and extends laterally through said side plate.

What we claim is:—

1. A trough adapted to extend transversely of a car-roof-frame, which trough is provided at each end with a baffle-member which extends up and down said trough.

2. A metal carline comprising a trough provided at each end with an end flange 90 which is arranged transversely of the carline, said carline having a baffle-member which extends up and down said flange at the outer side of the flange and is arranged between and spaced from the sides of the 95 trough.

3. A metal carline provided at each end with a downwardly projecting end flange which is arranged transversely of the carline, which carline is provided at the top 100 with two laterally and outwardly projecting side flanges which are arranged at opposite sides respectively and extend longitudinally of the carline, said carline having a baffle-member which extends up and down the 105 aforesaid end flange at the outer side of the flange and projects above the adjacent ends of the side flanges of the carline.

4. A metal carline comprising a trough provided at each end with an end flange 110 which is arranged transversely of the carline, said carline being provided with a baffle-member which extends up and down said flange at the outer side of the flange and below the bottom of the trough.

5. A metal carline comprising a trough provided at each end with an end flange which is arranged transversely of the carline, said flange being provided with an outwardly offset portion which extends up and down the outer side of the flange and is arranged between and spaced from the sides of the trough.

6. A metal carline comprising a trough provided at each end with a downwardly projecting flange which is arranged transversely of the carline, the sides of said trough diverging toward said flange, and the carline having a baffle-member which extends up and down said flange and is ar- 130

- ranged centrally between said diverging sides of the trough.
7. A metal carline comprising a trough provided at each end with an end flange which is arranged transversely of the carline, said flange being provided with an outwardly offset portion which extends up and down the outer side of said flange and below the trough.
- 10 8. A metal carline comprising a trough provided at each end with a downwardly projecting end flange which is arranged transversely of the carline, which trough has its sides diverging toward said flange and is provided at the top with two laterally and outwardly projecting side flanges which are arranged at opposite sides respectively and extend longitudinally of the trough, the aforesaid end flange being provided at its 15 outer side with a baffle-member which is arranged centrally between the sides of the trough and projects above the adjacent ends of the aforesaid side flanges.
9. A metal carline provided at each end 20 with a downwardly projecting end flange which is arranged transversely of the carline, said carline having a hump which extends up and down said flange and inwardly longitudinally of the carline and is provided 25 on top with a seat for a roofing-cap.
10. A metal carline comprising a trough provided at each end with a downwardly projecting end flange which is arranged transversely of the carline, said carline having a hump which extends up and down and 30 is arranged at the outer side of said flange between and spaced from the sides of the trough, said hump projecting above the bottom of the adjacent portion of the trough 35 and extending inwardly longitudinally of said portion of the trough centrally between the sides of the trough.
11. A metal carline comprising a trough provided at each end with a downwardly 40 projecting end flange which is arranged transversely of the carline, said carline having a baffle-member which extends up and down and is arranged at the outer side of said flange between and spaced from the 45 sides of the trough, said baffle-member extending inwardly longitudinally of the bottom of the trough and provided on top with a seat for a roofing-cap.
12. A metal carline comprising a trough 50 provided at each end with a downwardly projecting end flange which is arranged transversely of the carline, said carline having a hump which extends up and down the outer side of said flange and inwardly longitudinally of the bottom of the trough, the 55 hump having its portion which extends longitudinally of the trough gradually increased in height toward said flange and arranged between and spaced from the sides 60 of the trough.
13. A metal carline comprising a trough provided at each end with a downwardly projecting end flange which is arranged transversely of the carline and has a laterally and outwardly projecting lower portion, which trough has its sides diverging toward said flange, the carline having a baffle-member extending from said projecting portion of the flange upwardly and thence extending inwardly longitudinally of the bottom of the trough centrally between the sides of the trough, said baffle-member having its portion which extends longitudinally of the trough decreased in width toward its inner extremity.
14. A metal carline comprising a trough provided at each end with a downwardly projecting end flange which is arranged transversely of the carline, said flange being provided centrally between its side edges with an outwardly offset portion which extends from a point below the bottom of the trough upwardly to a point above said bottom, and the trough being provided centrally between its sides with an upwardly offset portion which extends longitudinally of the trough and connects with the offset portion of the aforesaid flange.
15. A metal carline comprising a trough provided at each end with a downwardly projecting end flange which is arranged transversely of the carline and has a laterally and outwardly projecting lower portion, said flange being provided with a laterally and outwardly offset portion which extends from said projecting portion of the flange upwardly, and the trough being provided centrally between its sides with an upwardly offset portion which extends longitudinally of the trough and connects with the aforesaid offset portion of the aforesaid flange.
16. A trough adapted to extend transversely of a car-roof-frame, which trough is provided at each end with a baffle-member arranged adjacent the bottom of the trough and extending upwardly above said bottom.
17. The combination, with the two laterally spaced side plates of a car-roof-frame, and a trough extending between and to the outer sides of the side plates, of baffle-members extending up and down said trough at the outer sides of the side plates.
18. The combination, with the two laterally spaced side plates of a car-roof-frame, and a trough extending between and to the outer sides of said plates, of baffle-members extending up and down at the outer sides of the side plates and arranged adjacent the bottom of the trough, said baffle-members projecting upwardly from said bottom.
19. The combination, with the two laterally spaced side plates of a car-roof-frame, of a metal carline comprising a trough extending between and connected to said side

plates and provided at each end with an end flange which is arranged opposite the outer side of the adjacent side plate, said flange being provided with an outwardly offset portion which extends upwardly from a point below the bottom of the trough and is provided below said bottom with a lateral bolt-hole, said side plate being provided with a lateral bolt-hole which registers with the bolt-hole in the offset portion of the adjacent end flange.

20. The combination, with the two laterally spaced side plates of a car-roof-frame, car-siding overlapping the outer sides of the lower portions of the side plates, and fascia covering the top of the car-siding, of a metal carline comprising a trough extending between the outer sides of said side plates at the top of the side plates and provided at each end with a flange which is arranged opposite the outer side of the adjacent side plate and over the adjacent fascia, the carline being provided with a baffle-member extending up and down between said fascia and the bottom of the trough.

21. The combination, with the two laterally spaced side plates of a car-roof-frame, of a metal carline comprising a trough extending through the upper portions of said side plates and provided at each end with an end flange which overlaps the outer side of and constitutes a lateral abutment for the adjacent side plate, said carline being provided with a baffle-member which is arranged at and extends up and down the outer side of said end flange and projects at the outer side of the adjacent side plate upwardly above said side plate.

22. The combination, with the two laterally spaced side plates of a car-roof-frame,

car-siding overlapping the outer sides of the lower portions of the side plates, and fascia covering the top of the car-siding, of a metal carline comprising a trough extending through the upper portions of said side plates and provided at each end with a flange which overlaps the outer side of and constitutes a lateral abutment for the adjacent side plate and has a laterally and outwardly projecting lower portion over the adjacent fascia, the carline being provided with a baffle-member which is arranged at the outer side of the aforesaid flange and extends from the upper side of said projecting portion of said flange to a point above the adjacent portion of the bottom of the trough.

23. The combination, with the two laterally spaced side plates of a car-roof-frame, of a metal carline comprising a trough extending through and secured to said side plates and provided at each end with a downwardly projecting end flange which overlaps the outer side of and constitutes a lateral abutment for the adjacent side plate, said flange being provided centrally between its side edges with an outwardly offset portion which extends upwardly from a point below the bottom of the trough and is provided below said bottom with a lateral bolt-hole, each side plate being provided with a lateral bolt-hole which registers with the bolt-hole in the offset portion of the adjacent end flange.

Signed by us at Cleveland, Ohio, this third day of July, 1912.

WILLIAM S. BIDLE.
